UNITED STATES PATENT OFFICE.

EDWARD I. HORSMAN, JR., OF NEW YORK, N. Y., ASSIGNOR TO E. I. HORSMAN CO., OF NEW YORK, N. Y., A CORPORATION OF NEW YORK.

DESIGN FOR A DOLL.

42,325.

Specification for Design. Patented Mar. 19, 1912.

Application filed January 12, 1912. Serial No. 670,950. Term of patent 3½ years.

To all whom it may concern:

Be it known that I, EDWARD I. HORSMAN, Jr., a citizen of the United States, and resident of the borough of Manhattan, city, county, and State of New York, have invented a certain new, original, and ornamental Design for a Doll, of which the following is a specification.

Reference is to be had to the accompanying drawing which shows a doll embodying my new design.

The design comprises a doll clothed in a short dress on which a band extends across the chest and up to each shoulder. A series of doll figures represented as clothed in dresses, waist and trousers and bloomers or rompers and in different positions are produced on said band.

I claim:

The ornamental design for a doll as shown and described.

In testimony whereof, I have hereunto set my hand in the presence of two subscribing witnesses.

EDWARD I. HORSMAN, JR.
